D12-203. OR D 13,420 EX

Design No. 13,420, dated November 14, 1882.

UNITED STATES PATENT OFFICE.

JOHN L. POPE, OF CLEVELAND, OHIO.

DESIGN FOR A CARRIAGE-STEP.

SPECIFICATION forming part of Design No. 13,420, dated November 14, 1882.

Application filed August 2, 1882. Term of patent 14 years.

To all whom it may concern:

Be it known that I, JOHN L. POPE, of Cleveland, in the county of Cuyahoga and State of Ohio, have invented and produced a new and original Design for Carriage-Steps, of which the following is a specification, reference being had to the accompanying photographic illustration, forming part thereof.

My invention relates to a new design for carriage-steps; and it consists in ornamenting the upper surface thereof with a series of raised rings and curved ribs, the effect of which ornamentation is the appearance of a border to the step, composed of elliptically-shaped figures and intertwinement ornamentation composed of similarly-shaped figures, all as will be herein-after more fully specified.

In the accompanying photograph the eye of an observer will readily discern the nine round intertwining and raised figures, which I have marked 1 2 3 4 5 6 7 8 9, respectively, as well as the twelve curved ribs or scallops that are marked with the letters *a a a a*, &c., and he

will not fail to observe that the result of the combination of these two elements is the 25 production of a chain of elliptically-shaped ribbed figures 1 *a*, 2 *a*, 3 *a*, &c., running all around or bordering the step. A row of these elliptically-shaped figures will be found along the line *x x* and another row along the line *y y*, 30 while two or more transverse rows at the lines *w w* and *z z* may be readily seen.

The openings between the ribbed figures may be dispensed with without affecting the novelty of my design.

I claim as my invention and desire to secure by Letters Patent—

A design for a carriage-step top, composed of raised rings and curved ribs, arranged substantially as shown and described.

In testimony whereof I have hereunto set my hand this 31st day of May, 1882.

JOHN L. POPE.

In presence of—

A. A. POPE,

C. M. COPP.
